METHOD FOR MAKING RETAINER LOCKS

Otto R. Schoenrock, Chicago, Ill.

Application May 19, 1941, Serial No. 394,063

1 Claim. (Cl. 153—2)

My invention relates to a method and apparatus for making retainer locks such as the split tapered collars or bushings used in valve assemblies for securing the spring retainer plate in place on the valve stem.

One of the objects of my invention is to provide an improved method by means of which these retainer locks may be produced rapidly and accurately.

Further objects and advantages of the invention will be apparent from the description and claim.

In accordance with my invention, a metal strip or bar having substantially the desired cross section of the finished container lock is subjected to a bending and forming operation, by means of which a half circle bend is formed on the end of the bar and this half circle bend is thereafter sheared from the bar to form a section of the lock. If desired, the edges of the sheared off lock section may thereafter be ground to insure the proper size of the sections.

In the drawing in which my invention is illustrated:

Fig. 1 is a vertical sectional view showing the bending apparatus;

Fig. 2 is a vertical sectional view showing the severing and grinding apparatus;

Fig. 3 is a view of a partially formed end of the bar;

Fig. 4 is a side view of the completely formed end of the bar;

Fig. 5 is a view showing a finished lock member severed from the bar and ground;

Fig. 6 is a view from the right of Fig. 5;

Fig. 7 is a cross sectional view of the bar substantially on the line 7—7 of Fig. 4; and

Fig. 8 is a horizontal section substantially on the line 8—8 of Fig. 2.

Referring to the drawing in detail, the construction shown in Fig. 1 is for the purpose of forming a half circle bend in the end of the bar from which the lock sections are formed. The construction shown in Fig. 2 comprises apparatus for severing the half circle bend from the end of the bar to form lock sections and for grinding the edges of the lock sections.

Referring first to Fig. 1, the apparatus here shown comprises a guide block or frame 1, a die 2 having a half circle bend forming surface, a retractable stop 3 against which the end of the bar 4 is pressed for positioning it so that the right length of material will be provided for forming the bend, a vertically reciprocable punch or forming tool 5 having a quadrantal conoidal

forming surface 6 for forming a quarter circle bend 7 in the end portion of the bar as shown in Fig. 3, a horizontally reciprocable punch 8 or forming tool having a half circle conoidal surface for pressing the end of the bar against the forming die to complete a half circle bend 9 in the end of the bar, as shown in Fig. 4, and a yieldable presser foot 10 which comes down on the bar 4 when the forming dies are operated to hold the bar against displacement when the end is being bent. The stop member 3 is withdrawn horizontally in timed relation to the punch 6 so as not to obstruct its movement. The passage 11 into which the bar is inserted is wide enough so that the bar has a slip fit in this passage but is held securely against side slip.

The construction shown in Fig. 2 comprises a mounting block 12 having a passage 13 into which the bent end of the bar is inserted after it has been withdrawn from the apparatus shown in Fig. 1, a shearing edge 14 at the inner end of this passage, a spring-pressed stop block 15 against which the bent end of the bar is pressed when the bar is to be sheared, a guide passage 16 into which the sheared-off lock sections 17 are forced when severed from the end of the bar 4, a reciprocating shearing blade 18 cooperating with the shearing edge 14, a rotatable grinding tool 19 operating in a recess in the block 12 for grinding the edges of the lock sections as they are forced down the guide passage 16, and a spring presser foot 20 similar to the presser foot 10 shown in Fig. 1 for holding the bar 4 in position when the end is being sheared off. The yielding abutment or stop-block 15 enables the half circle bend 9 to be brought into position by the operator for shearing as shown in Fig. 2, and also holds the edge of the half circle bend snugly against the face 21 of the block to insure that the shear will be made at the proper point.

In order to adjust the grinding tool 19 accurately and insure that the block sections are ground to proper size, the bearing 22 in which the grinder shaft 23 rotates is made axially adjustable by mounting it in an axially adjustable sleeve 24. The adjustment of this sleeve is effected by means of a threaded connection with the block. It may be held in the desired adjusted position by means of a lock nut 25.

The presser foot 20 may be of any usual or suitable construction comprising a tubular presser member 26 telescopically mounted on a pin 27 carried by the punch head 28. A coil compression spring 29 is provided to hold the presser foot 20 yielding against the bar 4. The yielding abut-

ment 15 is pressed to the right by means of a coil compression spring 30, one end of which bears on the bracket 31, the other end of which bears against a collar 32 on the block 15.

In operation, the end of the bar is inserted into the passageway 11 in the block shown in Fig. 1 until the end of the bar is stopped by engaging the abutment 3. The operator then puts the press in operation, causing the stop 3 to be withdrawn, the vertically reciprocating forming tool 5 to be brought down to form a quarter circle bend in the end portion of the bar, the forming tool 5 withdrawn, the horizontally reciprocating forming tool 8 operated to press the end portion of the bar into the shape shown in Fig. 1, and the horizontally reciprocating forming tool 8 withdrawn to enable the operator to withdraw the end of the bar from this forming apparatus.

The operator then inserts the end of the bar with the half circle bend formed therein into the guide passage 13 in the apparatus shown in Fig. 2, bringing the half circle bend down into the position shown in which the spring pressed plunger or stop-block 15 will hold the edge of the end of the bar snugly against the face 21 of the block. The operator then puts the apparatus into operation to cause the shearing blade 18 to descend, carrying with it the spring presser foot 20 for holding the bar firmly during the shearing operation. The shearing edge shears the half circle bend 9 from the bar and forces any previously sheared-off lock sections ahead of it down the passageway 16. As the lock sections move downwardly in the passage, they are subjected to the grinding action of the rotatable face grinding tool 19 which grinds the edges of the lock sections smoothly and insures that the lock sections will be of the proper size.

As indicated in Figs. 1, 5, 6, 7, and 8, the dies may be so designed that the retainer lock will

have a conoidal surface for fitting in a correspondingly shaped seat and the bar 4 may be provided with internal beads 33 for fitting in circumferential grooves in the valve stem.

5 In the claim where the expressions "quarter circle," "half circle" and "quadrantal" are used, they are to be understood as broad enough to cover obvious approximations.

10 Further modifications will be apparent to those skilled in the art and it is desired, therefore, that the invention be limited only by the scope of the appended claim.

15 Having thus described my invention, what I claim and desire to secure by Letters Patent is:

A method for making a valve spring retaining lock section from a straight bar of a length sufficient to form a plurality of lock sections, said bar having one flat face and having a longitudinally-extending shoulder to be bent for arcuate engagement with a circumferentially-extending shoulder on the valve stem and having its opposite face extending at an oblique angle with respect to said flat face, comprising bending and shaping the end of the bar to form a half-circle bend with the unbent straight remaining portion extending substantially tangentially to the bent portion, with the point of tangency substantially diametrically opposite the free end of the half-circle bend, and with the flat face of the bar 20 forming a conoidal outer surface for engagement with a conoidal inner surface on the valve spring retainer, said opposite face forming a cylindrical surface of engagement with the valve stem, and thereafter severing the half-circle bend from the end of the bar substantially on a plane through the axis of the half-circle bend and substantially at the point of tangency and substantially diametrically opposite the free end of the half-circle bend.
